CLAIM

We claim the ornamental design for a nozzle tip for a pressure washer, as shown and described in FIGS. 1-5.

DESCRIPTION

FIG. 1 is a perspective view of a nozzle tip for a pressure washer according to a first embodiment of the present invention.

FIG. 2 is a front view of the nozzle tip shown in FIG. 1. FIG. 3 is a side view of the nozzle tip shown in FIG. 1, the opposite side view being identical.

FIG. 4 is a bottom view of the nozzle tip shown in FIG. 1; and,

FIG. 5 is a top view of the nozzle tip shown in FIG. 1. The broken line showing of the environment is for illustrative purposes only and forms no part of the claimed design. The broken lines which define the boundaries of the claimed design form no part thereof.
